UNITED STATES PATENT OFFICE.

OTTO M. BECK, OF NEW YORK, N. Y.

FIREPROOF WINDOW FOR WAREHOUSES.

1,128,402.

Specification of Letters Patent. Patented Feb. 16, 1915.

Application filed July 3, 1912. Serial No. 707,563.

To all whom it may concern:

Be it known that I, OTTO M. BECK, a citizen of the United States of America, residing in New York, in the borough of Brooklyn, county of Kings, and State of New York, have invented certain new and useful Improvements in Fireproof Windows for Warehouses, of which the following is a specification.

10 This invention relates to fireproof windows for warehouses and other purposes in which the sash frame comprises intersecting T ribs of wrought iron or steel, glass panes supported on the flanges of said ribs and 15 bolted angle plates clamping the parts together.

The invention has reference more specifically to the peculiar construction at the intersections of the T ribs.

20 In the accompanying drawing, Figure 1 represents a front-elevation of my improved fireproof window for warehouses, Fig. 2 is a vertical transverse section on line 2, 2, Fig. 1, Fig. 3 represents on a large scale a vertical section on line 3—3 of Fig. 1. Fig. 4 represents on a large scale a horizontal section on line 4—4 of Fig. 1. Fig. 5 is a perspective view on a large scale of a fragment of an upright rib with its peculiar triangular slot and a fragment of a transverse rib passed through said slot and having its lateral flanges swaged on either side of the main web of the vertical rib, the angle plates being omitted for purposes of illustration.

25 Fig. 6 is a perspective view on a large scale of fragments of a vertical rib, a transverse rib, glass panes, vertical angle plates on opposite sides of the vertical ribs and closing the slot therein and horizontal angle plates 40 on the transverse ribs, and bolts securing said parts.

Similar letters of reference indicate corresponding parts throughout the different figures of the drawing.

45 Referring to the drawing, *a* represents the upright ribs and *b* the transverse ribs of the frame of my improved fireproof window for warehouses and other buildings. The upright and transverse ribs *a*, *b* are composed of T bars which are rolled from steel or other suitable metal. The inwardly-projecting webs *a*¹ of the T-shaped uprights *a* of the frame are provided at the points

where they are intersected by the transverse ribs *b* with triangular recesses *a*², as shown 55 clearly in Fig. 5, so that the transverse ribs *b* and their webs *b*¹ can be passed through the upright ribs forming the frame. The heads of the transverse ribs *b* are punched up at their edges after the parts are connected, so as to form projections *b*² for holding the transverse ribs in proper position in the webs of the upright ribs. The outer faces of the top flanges or heads of the cross ribs rest against the inner faces of the top flanges or heads of the main ribs, which makes a strong construction, there being no cutting away or recessing of said heads or flanges. Each individual section or panel formed by the frame of the window is 70 closed by a pane *e* of wire-glass, which panes are supported against the heads of the upright and transverse ribs by means of angle-irons *d*, *d*¹ that are attached to the webs by means of bolts *d*², said angle-irons being 75 made of the proper size so as to extend from the web of one transverse rib to the other and between the webs of the upright ribs, as shown in Fig. 6. The angle-irons *d*, *d*¹ hold the wire-glass panes firmly in position in 80 the individual sections of the frame. The vertical angle plates *d* serve a double function of clamping the parts together and of closing the wide openings of the slots *a*² in the web *a*¹ of the vertical rib *a* on opposite 85 sides of the web *b*¹ of the transverse rib *b*. The space formed between the heads of the vertical ribs *a* and the adjacent portions of the wire-glass panes is filled up with a layer 90 of putty, also the space between the ends of the panes and the webs of the transverse ribs *b*, so as to furnish a water-tight connection of the panes with the ribs of the frame. In one or more panels of the window the glass panes may be provided with auxiliary 95 frames which are hinged or pivoted to the main-frame so as to permit the opening of the same for establishing ventilation when required; or the entire frame may be hinged at one side or pivoted to center top and bottom pivots for opening the window, or they may be balanced by counter-weights, or closed by springs when weights are not desired, and closed by suitable locking devices.

100 My improved fireproof window combines

a strong and solid construction with simplicity and ease of manufacture, is capable of resisting injury by fire or water, and provides a very reliable window for warehouses and other buildings.

I claim:

1. In a fireproof window the combination of metallic T ribs having wide webs, auxiliary T ribs intersecting therewith, the wide webs having triangular closed slots adapted to fit and receive said auxiliary T ribs, and angle plates disposed on opposite faces of said wide webs and serving to close the exposed portions of said triangular slots at opposite sides of said auxiliary ribs.

2. A fireproof window comprising main metallic T ribs having wide webs, auxiliary metallic T ribs intersecting therewith, the wide webs having triangular closed slots adapted to fit and receive said auxiliary T ribs, glass panes disposed in the panels formed by said intersecting ribs, said panes resting on the flanges of the auxiliary ribs, and angle plates clamped against opposite faces of said wide webs and resting against said panes, said angle plates uniting said parts and closing the exposed portions of

said slots at opposite sides of said auxiliary ribs.

3. A fireproof window comprising main metallic T ribs having wide webs, auxiliary metallic T ribs intersecting therewith, the wide webs having triangular closed slots adapted to fit and receive said auxiliary T ribs, glass panes disposed in the panels formed by said intersecting ribs, said panes resting on the flanges of the auxiliary ribs, angle plates clamped against opposite faces of said wide webs and resting against said panes, said angle plates uniting said parts and closing the exposed portions of said slots at opposite sides of said auxiliary ribs, layers of putty disposed between the margins of said panes and the heads of said metallic ribs, and bolts clamping said angle plates and ribs.

In testimony, that I claim the foregoing as my invention, I have signed my name in presence of two subscribing witnesses.

OTTO M. BECK.
